ARTICLE MARKING MECHANISM

Felix Huntar, Livingston, and Gustav Otto Frey,
Newark, N. J., assignors to American Can Company,
New York, N. Y., a corporation of New Jersey

Application December 21, 1949, Serial No. 134,281

8 Claims. (Cl. 101—35)

1

The present invention relates to a mechanism for marking articles such as containers with an identifying legend, symbol or mark and has particular reference to a marking device having a rocker motion.

An object of the invention is the provision of a marking mechanism which is particularly adapted for use in marking hollow fragile articles and which requires no backing up pressure means against the marking die, other than the article support.

Another object is the provision of such a marking mechanism wherein the marking device is actuated with a rocking motion so that the articles to be marked may be operated upon while they are at rest or held stationary at a marking station of the mechanism.

Another object is the provision of such a marking mechanism wherein the articles to be marked may be passed through the mechanism in a continuous procession, each article stopping only momentarily at a marking station for the marking operation, so that the mechanism as a unit may be readily utilized as a part of a more elaborate machine for performing other operations upon the articles.

Numerous other objects and advantages of the invention will be apparent as it is better understood from the following description, which, taken in connection with the accompanying drawings, discloses a preferred embodiment thereof.

Referring to the drawings:

Figure 1 is a plan view of a marking mechanism embodying the instant invention, with parts broken away and parts shown in section;

Fig. 2 is a top plan view of an article showing an identifying mark as applied in the mechanism shown in Fig. 1;

Fig. 3 is a sectional view taken substantially along the broken line 3—3 in Fig. 1, with parts broken away;

Fig. 4 is an enlarged side view of the marking parts of the mechanism shown in Fig. 1, with parts broken away, and with the upper end of an article in marking position;

Fig. 5 is a sectional view taken substantially along the broken line 5—5 in Fig. 4, with parts broken away;

Fig. 6 is a horizontal section taken substantially along the broken line 6—6 in Fig. 4;

Fig. 7 is an enlarged transverse section taken substantially along the line 7—7 in Fig. 6, with parts broken away;

Fig. 8 is a fragmentary view similar to Fig. 4

and showing the moving parts in a different position;

Fig. 9 is an enlarged sectional view taken substantially along the line 9—9 in Fig. 4;

Fig. 10 is a greatly enlarged sectional view taken substantially along the line 10—10 in Fig. 6, with parts broken away; and

Fig. 11 is a greatly enlarged schematic sectional view taken substantially along the broken line 11—11 in Fig. 7, with parts omitted and parts broken away.

As a preferred and exemplary embodiment of the instant invention the drawings illustrate a marking mechanism for printing a permanent, legible identifying mark, for example the mark A "Saturday" (Fig. 2) on an article B to be marked. By way of example, the drawings show the article to be marked as a paraffin coated fibre milk container of the character disclosed in 15 United States Patent 2,085,979 issued July 6, 1937, to John M. Hothersall although the invention is equally well adapted to marking a great variety of other articles. The mark A imprinted on the container is shown as a day of the calendar week 20 and preferably is applied to a sealing or closure element C on the top of the container.

In the preferred showing of the mechanism the containers are fed in a continuous procession in upright position with their tops uppermost and are advanced intermittently into a marking station D (Fig. 1). The advancement of the containers is effected by a star wheel or turret 20 (Figs. 1 and 3) having a pair of spaced and parallel turret disks 21 mounted on the upper end of an intermittently rotatable shaft 22 carried in a bearing 23 formed in a frame 24 which may be the main frame of a filling or other machine which performs a previous operation upon the container. The shaft 22 may be rotated in any suitable manner.

The outer peripheries of the turret disks are formed with vertically aligned pockets 26 for receiving and advancing the containers. The containers are introduced into these pockets in any suitable manner. While in the pockets, the containers are supported on a curved table 27 secured to the frame 24. The table is formed with inner and outer guide ledges 28. Curved inner and outer guide rails 29, 30 disposed adjacent the path of travel of the upper end of the advancing containers, cooperate with the table guide ledges 28 in retaining the containers in their turret pockets during their advancement.

After a container marking operation at the marking station D, the turret disks 21 advance

the marked containers onto a continuously rotating discharge disk 35 (Fig. 1) carried on a shaft 36 journaled in the main frame 24. The containers are guided into position onto this disk as they leave the marking station, by continuations of the guide rails 29, 30, which continuations curve around the disk 35. The discharge disk 35 transfers the marked containers to a continuously moving conventional belt conveyor 37 (Fig. 1) which carries the containers to any suitable place of deposit.

Marking of a container B with a legend A at the marking station D is effected while the container is in its turret pockets 26 and while the container and the turret are at rest between intermittent rotation of the turret. This marking operation is performed by a rocker type marking device which is located at the marking station. The marking device is housed in a stationary marker frame 41 (Figs. 1, 3, 4, 5, 6, 7, 8) which includes a pair of spaced horizontal frame members 42 between which the upper ends of the containers pass during their advancement through the mechanism. The marker frame 41 is secured to an upright bracket 44 which extends up from the main frame 24.

The frame members 42 support a two-piece rocker head 46 (Figs. 6 and 7) comprising a main body 47 and an end cap 48 which operate as a unit, the cap being fastened to the body. The rocker head 46 is freely mounted on the rocker frame for rocking movement thereon. For this purpose the rocker head body 47 and its cap 48, adjacent the frame members 42, are formed with curved rocker elements or rockers 51 which are disposed in spaced relation and which engage against a pair of similarly spaced, flat rocker rails 52 formed on the frame members (see Fig. 11). In order to prevent slipping between the rockers 51 and the rails 52, the head body 47 and its cap 48 carry segment gears 54 which mesh with gear racks 55 secured to the frame members 42 adjacent the rocker rails 52.

Rocking of the rocker head 46 is effected preferably by a carriage 57 (Figs. 4, 6 and 7) which extends across the rocker frame members 42 above the rocker head. This carriage is formed with side arms 58 which terminate in bearings 59 surrounding trunnions 61, 62 of the frame members 42. The trunnion 61 is an integral part of its frame member, while trunnion 62 is a separate part secured in place in its frame member. The longitudinal axes of the trunnions align with each other and with the top rocker surfaces of the rocker rails 52 to effect proper rocking movement of the rocker head 46.

The rocker head 46 is pressed against the frame members 42 under constant pressure by a compression spring 65 (Fig. 7) which is interposed between the head and the carriage 57. One end of the spring 65 is seated in a recess 66 formed in the rocker head while the opposite end is disposed in a threaded bore 67 formed in the carriage. An adjusting screw 68 disposed in the bore 67 is provided for adjusting the pressure of the spring on the rocker head.

The upper end of the rocker head 46, opposite its rockers 51, is provided with a pair of spaced and parallel upright arms 71 (Figs. 6, 7 and 8) which at their upper ends carry slide blocks 72. These blocks are slideably disposed in upright slideways 73 formed in enlarged portions 74 of the carriage arms 58. The slide blocks 72 and slideways 73 thus provide a loose actuating connection between the rocker head 46 and the car-

riage 57 and rock the upper end of the head while permitting the spring 65 to press the head against its rocker frame members. Through this loose connection the rocker head 46 is rocked back and forth on the rocker rails 52 by the carriage 57.

Rocking movement of the carriage 57 is effected through cam action by a face cam 75 (Figs. 4 and 8) which is mounted on a continuously rotating cam shaft 76 journaled in a bearing 77 formed on the side of the rocker frame 41. The shaft is rotated in any suitable manner in time with the turret shaft 22 so that the cam shaft 76 and the cam 75 mounted thereon makes one revolution every time the turret shaft 22 makes a partial rotation and thereby advances a container through one step. For this purpose the rocker carriage 57 is connected by a link 78 to one arm 79 of a bell crank 80 mounted on a pivot pin 81 secured in the rocker frame 41 (see Fig. 8). Another arm 82 of the bell crank carries a cam roller 83 which operates in a cam groove 84 of the face cam 75. Thus every time the cam 75 makes one revolution, it rocks the bell crank 80 and through the link 78 in turn rocks the carriage 57 and the rocker head 46 loosely connected thereto.

In order to effect the marking of the containers, the rocker head 46 carries a marking drum 87 (Figs. 7, 9 and 11) which is provided with a plurality of marking elements or dies 88 spaced around its periphery. The marking drum 87 is rotatably mounted in the marking head 46. This drum is formed with an axial tapered bore which extends entirely through the drum. At one end, the right as viewed in Fig. 7, the drum is supported by a trunnion 89 having a tapered plug 90 which is secured in the small end of the tapered bore. The trunnion extends beyond the drum and is journaled in a bearing formed in the marking head. At its opposite end, the left as viewed in Fig. 7, the drum is supported in a sleeve 91 which is secured to the head cap 48. The sleeve surrounds this end of the drum. The bottom of the marking head 46 is open as shown in Fig. 11 to permit a selected marking die 88 to extend beyond the head for marking purposes.

Provision is made to rotate the marking drum 87 in the marking head 46 to selectively locate a desired marking die 88 in marking position at the bottom of the marking head. For this purpose, the outer periphery of the marking drum 87, adjacent the trunnion 89, is formed with gear teeth 93 (Fig. 9) which mesh with a pinion 94 secured to an adjusting shaft 95 carried in a bearing 96 formed in the marking head. The end of the shaft opposite the pinion 94 is formed with a hollow head 97 adapted to receive a wrench or key or other tool suitable for rotating the adjusting shaft 95. By thus rotating the shaft 95 the pinion rotates the drum into any desired position. Markings or indicia 98 (Fig. 8) on the edge of the marking drum 87 are provided for visibly indicating which marking die is located in marking position. These markings 98 are visible only through an opening 99 (Figs. 4, 5 and 8) formed in the head cap 48. The marking showing through this opening is the same as the marking on the die 88 located in marking position at the bottom of the head 46.

After an adjustment of the marking drum 87, it may be locked in such marking position against inadvertent rotation. This locking of the drum preferably is brought about by a locking pin 101 (Fig. 10) which is engageable in any one of a

plurality of locking holes 102 (see also Fig. 9) formed in the marking drum 87 adjacent the end of the drum which is mounted in the sleeve 91. The locking pin 101 projects through a clearance opening 103 in the sleeve 91 and extends up through a hollow spring barrel 104 threadedly secured in the marking head 46. A compression spring 105 located in the barrel 104 and interposed between the barrel and a collar 106 formed on the pin, keeps the pin in place in the selected locking hole 102 and thus holds the marking drum in an adjusted position. The outer end of the pin 101 extends beyond the spring barrel 104 and carries a knob 107 for manually withdrawing the pin from locking position to effect an adjustment of the marking drum.

When marking articles having a paraffin-coated surface, such as the containers B, the marking elements or dies 88 preferably are heated and used in conjunction with a ribbon 111 carrying a transferable thermoplastic material. In the instant case heating of the dies 88 preferably is effected by an electric heating unit 112 (Fig. 7) which is located within the tapered bore of the marking drum 87. The heating unit is connected by wires 113, 114 to any suitable source of electric current. Heat generated by this unit is transferred by conduction through the marking drum 87 to the marking dies 88.

The thermoplastic coated ribbon 111 preferably is drawn from a reel 118 (Figs. 4 and 5) which is mounted on a short shaft 119 carried in a boss 120 formed on the marker frame 41. The ribbon from the reel extends downwardly over a pair of idler rollers 122, 123 carried on studs 124 secured in lugs 127, 128 which extend out from the frame 41 and one of the frame members 42 respectively (see also Fig. 6). The roller 123 is disposed adjacent the bottom of the marking head 46 and the ribbon extends substantially horizontally from this roller, across and below the bottom of the marking head to a third idler roller 131 disposed adjacent the opposite side of the marking head (shown in Figs. 4 and 6). This idler roller 131 is mounted on a stud 132 secured in a lug 133 which extends from the adjacent frame member 42. From the idler roller 131, the ribbon extends upwardly between a ribbon feeding or pulling roller 135 and a pressure roller 136 (Figs. 4 and 5) mounted on studs 137 secured in bosses 138 formed on the marking frame 41.

The feeding roller 135 is provided with a ratchet wheel 141 which is engaged by a pawl 142 mounted on a pivot pin 143 carried in an upright arm 144 of a bell crank 145. The bell crank is mounted on a pivot stud 146 secured in a lug 147 which extends from one of the bosses 138 (see Fig. 5). The pawl 142 is held under pressure against the ratchet wheel 141 by a tension spring 148 which is stretched between and engaged in the ends of lugs 149, 150 which extend outwardly from the pawl and the bell crank respectively.

An opposite arm 152 of the bell crank 145 carries at its outer end a button 153 which is located in the path of travel of and normally in engagement with (as best shown in Fig. 8) the head of an adjustable screw 154 secured in a lug 155 which projects out from the marker carriage 57. A spring 156 (Figs. 4, 5 and 8) having one end connected with the upright arm 144 of the bell crank 145 and its opposite end secured to the frame 41 keeps the button 153 in engagement with the screw 154.

Thus when the carriage 57 rocks forward through a marking stroke (toward the left as

viewed in Fig. 8), the screw 154 moves away from the button 153 and thus permits the spring 156 to rock the bell crank 145 in a clockwise direction and thus draws the pawl 142 toward the right as viewed in Fig. 8; the pawl riding over the teeth of the ratchet wheel 141 and coming to rest in the position shown in Fig. 4. When the carriage 57 rocks back (toward the right in Fig. 4) after a marking operation, the screw 154 engages the button 153 and rocks the bell crank 145 in a counterclockwise direction and thus pushes the pawl 142 forward (toward the left as viewed in Fig. 4). This movement of the pawl partially rotates the ratchet wheel 141 and thus pulls the ribbon and advances it sufficient to bring an unused portion into position under the marking die 88. The ribbon upon leaving the feeding or pull roller 135 may be torn off or directed to any suitable place of deposit.

In the operation of the above described marking mechanism, a container B upon being advanced into the marking station D is disposed directly under the marking device with the portion of the container to be marked in substantial vertical alignment with the selected marking die 88 in the marking head 46 and with the thermoplastic coated ribbon 111 interposed between the marking die 88 and the container as best shown in Fig. 8. During this advancement of the container into marking position at the station D, the marking head 46 and its associated parts are in the position shown in Fig. 8 to hold the selected marking die 88 in an elevated position above the path of travel of the container so as to clear the container as the latter advances into the marking station.

While the container B is at rest at the marking station D, the continuously rotating cam 75 rocks the marking carriage 57 forward, toward the left as viewed in Figs. 8 and 11. During this rocking movement, the rocker head 46 moves with the carriage, the rocker elements 51 rocking forward on the frame guide rails 52 and being guided against slippage by the segment gears 54 and racks 55. As the rocker head 46 thus rocks forward, the selected marking die 88, by virtue of its position in the rocker head, moves down against the ribbon 111 and presses the ribbon against the top of the container positioned at the marking station as best shown in Fig. 4. It is this rocking movement that imprints the mark A onto the container.

After the marking operation, as explained above, the cam 75 rocks the carriage 57 and its marking head 46, back through a return stroke, toward the right in Fig. 4. This return movement of the carriage and head lifts the marking die 88 upwardly away from the container and the ribbon and thus is clear of the marked container to permit removal of the container from the marking station. It is also this return movement that advances the ribbon for a subsequent marking operation as explained hereinbefore. This completes the cycle of operation of the marking device.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

We claim:

1. A mechanism for marking articles such as containers and the like with an identifying legend, the combination of a marker frame, a carriage including spaced side arms having trunnions for pivotal connection with said frame, a rocker head in said carriage between said side arms and having a curved rocker element resting on said frame for rocking movement with said carriage, said rocker head also moving in said carriage toward and away from the axis of said trunnions, means for maintaining said rocker element in engagement with said frame during its rocking movement, actuating devices for rocking said carriage and said head through its rocker element on said frame, and a marking instrumentality carried in said head and movable through the rocking action of said head toward and away from an article held stationary adjacent said frame for marking an identifying legend on said article.

2. A mechanism for marking articles such as containers and the like with an identifying legend, the combination of a marker frame, a carriage pivotally connected to said frame in spaced pivots along one side of the carriage, a rocker head in said carriage and having a curved rocker element resting on said frame in between said carriage pivots for rocking movement with said carriage, said rocker head also having independent movement in said carriage, means carried by said carriage at the side opposite said pivots and operable against said rocker head for maintaining said rocker element in engagement with said frame, actuating devices for rocking said carriage to rock said head through its rocker element on said frame, meshing rack and gear elements secured to said frame and said head respectively and disposed alongside of said curved rocker element for controlling the rocking action between said rocker element and said frame against slippage, and a marking instrumentality carried in said head and movable through the rocking action of said head toward and away from an article held stationary adjacent said frame for marking an identifying legend on said article.

3. A mechanism for marking articles such as containers and the like with an identifying legend, the combination of a marker frame, a carriage pivotally mounted on said frame, a rocker head carried by said carriage and having rocking movement on the frame, meshing rack and gear elements secured to said frame and said head respectively, means interposed between said carriage and said rocker head for maintaining said rack and gear elements in meshing engagement, actuating devices connected with said carriage for moving the carriage thereby rocking said head on said rack and gear elements, and a marking instrumentality carried in said head and movable through the rocking action of said head toward and away from an article held stationary adjacent said frame for marking an identifying legend on said article.

4. A mechanism for marking articles such as containers and the like with an identifying legend, the combination of a marker frame, a carriage having side members pivotally connected to said frame, a rocker head carried within said carriage and confined against lateral displacement by said side members, said rocker head having a curved rocker element resting on said frame for rocking movement on said frame, means connected between said carriage and said

rocker head for maintaining said curved rocker element in engagement with said frame, actuating devices operable on said carriage for rocking the carriage and the rocker head in unison, and a marking instrumentality carried in said head and movable therewith during its rocking movement for marking an identifying legend on an article held stationary in the path of travel of said marking instrumentality.

5. A mechanism for marking articles such as containers and the like with an identifying legend, the combination of a stationary marker frame, a pair of spaced rocker rails on said frame, a pair of gear racks on said frame disposed one adjacent each of said rails, a rockable carriage extending across said frame and pivotally mounted on said frame on opposite sides thereof adjacent said rocker rails, a rocker head confined within said carriage, said rocker head adjacent said frame having a pair of curved rocker elements engaging with said rocker rails and a pair of segment gears meshing with said gear racks, said rocker head having movement within said carriage in a sliding connection including slide blocks and slideways, pressure means interposed between said carriage and said head for yieldably maintaining said rocker elements in engagement with said rocker rails, actuating devices connecting with said carriage for rocking said carriage and said head through a marking stroke and thence through a return stroke, and a marking instrumentality carried in said head and projecting therefrom between said rails and movable with said head during its rocking movement for marking an identifying legend on an article held stationary in the path of travel of said marking instrumentality.

6. A mechanism for marking articles such as containers and the like with an identifying legend, the combination of a marker frame, a rocker head having longitudinally spaced curved rocker elements resting on said frame for lateral rocking movement thereon, means for maintaining said rocker elements in engagement with said frame, a rotatable marker drum carried in said head and extending longitudinally of the head, said drum having a plurality of circumferentially spaced marking instrumentalities located between the spaced elements of said rocker head, means in said head for rotating said drum for selectively locating a marking instrumentality in operative position with the located marking instrumentality projecting beyond said rocker head, means for locking said drum against rotation after an adjustment thereof, and actuating devices for rocking said head on said frame for moving the selectively located marking instrumentality toward and away from an article held stationary adjacent said frame for marking an identifying legend on said article.

7. A mechanism for marking articles such as containers and the like with an identifying legend, the combination of a marker frame, a carriage pivotally mounted on said frame, a rocker head mounted in said carriage and having movement with the carriage, said rocker head having a curved rocker element resting on said frame for rocking movement thereon, means for maintaining said rocker element in engagement with said frame, a marking instrumentality carried in said head and movable therewith, a heating element also disposed in said head for heating said marking instrumentality, a ribbon carrying a thermoplastic marking material disposed adjacent said marking instrumentality, and

actuating devices for moving said carriage and for rocking said head on said frame for moving said marking instrumentality toward and away from an article held stationary adjacent said frame with the ribbon interposed between the marking instrumentality and the article to transfer some of the thermoplastic material from the ribbon to the article for marking an identifying legend on said article.

8. A mechanism for marking articles such as containers and the like with an identifying legend, the combination of a marker frame, a carriage pivotally mounted on said frame, a rocker head carried by said carriage and having a movement therewith, said rocker head having a curved rocker element resting on said frame for rocking movement thereon, means for maintaining said rocker element in engagement with said frame, actuating devices for moving said carriage and for rocking said head through its rocker element on said frame, a marking instrumentality carried in said head and movable through

the rocking action of said head toward and away from an article held stationary adjacent said frame for marking an identifying legend on said article, support means adjacent said rocker frame for supporting the article during the marking operation, and means for feeding and locating the article on said support for the marking operation and for removing the article after the marking operation.
